UNITED STATES PATENT OFFICE

WILLIAM R. CRAWFORD, OF KINGSPORT, TENNESSEE, ASSIGNOR TO BLUE RIDGE
GLASS CORPORATION, OF KINGSPORT, TENNESSEE, A CORPORATION OF NEW YORK

DESIGN FOR SHEET GLASS

Application filed July 3, 1929. Serial No. 31,931. Term of patent 14 years.

To all whom it may concern:

Be it known that I, WILLIAM R. CRAWFORD, a citizen of the United States, residing at Kingsport, in the county of Sullivan and State of Tennessee, have invented a new, original, and ornamental Design for Sheet Glass, of which the following is a specification, reference being had to the accompanying drawings forming part hereof.

Figure 1 shows the face of a section of a sheet of glass showing my new design.

Figure 2 is an enlargement of that portion of Figure 1 on which the ornamentation is applied.

Figure 3 is a vertical section on line 3—3 of Figure 2.

The design covers one entire face of the sheet of glass.

I claim:

The ornamental design for sheet glass as shown and described.

WILLIAM R. CRAWFORD.
